The ornamental design for a transceiver assembly, as shown and described.

DESCRIPTION

FIG. 1 is a front, top, left side isometric view of the transceiver assembly;

FIG. 2 is a top view thereof;

FIG. 3 is a front view thereof;

FIG. 4 is a left side view thereof;

FIG. 5 is a right side view thereof;

FIG. 6 is a back view thereof;

FIG. 7 is a back, bottom, right side isometric view thereof; and,

FIG. 8 is a bottom view thereof.

The evenly dashed broken lines immediately adjacent the shaded areas represent the bounds of the claimed design while all other evenly dashed broken lines are directed to environment and are for illustrative purposes only; the evenly dashed broken lines form no part of the claimed design.
